United States Patent

Des. 239,495
Patented Apr. 13, 1976

239,495

LITTER BASKET

Donald J. Shanklin, Granada Hills, Calif., assignor to Orion Industries, Inc.

Filed Nov. 27, 1974, Ser. No. 527,746

Term of patent 14 years

Int. Cl. D7—07

U.S. Cl. D7—189

Fig. 1

Fig. 2

Fig. 3

Fig. 4

Fig. 5

FIG. 1 is a perspective view of a litter basket showing my new design;

FIG. 2 is a rear elevational view thereof;

FIG. 3 is a right side elevational view thereof;

FIG. 4 is a top plan view thereof; and

FIG. 5 is a bottom plan view thereof.

I claim:

The ornamental design for a litter basket, substantially as shown and described.
